UNITED STATES PATENT OFFICE.

LEONARD E. DEMPSTER, OF SCHENECTADY, NEW YORK, ASSIGNOR TO GENERAL ELECTRIC COMPANY, A CORPORATION OF NEW YORK.

MERCURY-VAPOR LAMP.

974,037.

Specification of Letters Patent. Patented Oct. 25, 1910.

Application filed March 27, 1905. Serial No. 252,177.

To all whom it may concern:

Be it known that I, LEONARD E. DEMPSTER, a subject of the King of Great Britain, residing at Schenectady, county of Schenectady, State of New York, have invented certain new and useful Improvements in Mercury-Vapor Lamps, of which the following is a specification.

This invention relates to electrical apparatus of the type in which current is conducted through an evacuated chamber containing vapor of mercury or other vaporizable metal. It has been heretofore proposed to provide such tubes with a high resistance filament which, at starting, connects the two electrodes of the tube, but which may be separated from the mercury electrode, thereby forming an incipient arc at the surface of the mercury, which arc extends immediately to the co-operating electrode.

It is the object of this invention to provide an improved means for producing this incipient arc at the surface of the mercury electrode.

My improvement also embodies certain other novel features which will be pointed out more in detail in the following description taken in connection with the drawing which forms a part of this specification.

The figure shows an evacuated chamber or tube 1 provided with a carbon anode 2, a mercury cathode 3, and a high resistance filament 4 of carbon or other suitable material. A lower tubular extension 5 of the evacuated tube is surrounded by a solenoid 6 and is separated therefrom by a sleeve 7 of brass which serves as a mechanical support for the tube 1. Floating in the mercury electrode 3 is a glass plunger 8 comprising a lower compartment 9 hermetically sealed and containing a bundle of soft iron wires 10 which constitute an armature for the solenoid 6. The upper part 11 of the glass plunger 8 is open at the top and constitutes a cup for mercury. Dipping in this cup of mercury is the lower end of filament 4. A tube 12 of glass or other insulating material is supported from the side wall of the chamber 1 and surrounds the lower end 50 of filament 4 to protect it from the destructive action of arcing as hereinafter more fully set forth. The anode 2 is connected to the positive side of the current source through the magnetizing coil of an automatic cut-out 13, the armature 14 of which

serves to connect solenoid 6 to the positive side of the current source. The other terminal of solenoid 6 is connected to the negative side of the current source through a resistance 15, though if desired the solenoid 60 may be so proportioned that the resistance 15 is unnecessary. The mercury electrode 3 is connected to the negative side of the current source through a steadyng 65 resistance 16.

At starting, the various parts of the apparatus are in the position shown in the figure, and current flows from the source through solenoid 6, thereby drawing down the plunger 8 until the mercury outside the plunger 70 overflows the upper edge of cup 11 and makes contact with the mercury in the cup. This completes the circuit from the positive pole of the current source through the cut-out 13 and filament 4, thereby allowing current to flow from the mercury in cup 11 to the main body of mercury constituting the cathode and thence back to the current source through resistance 16. This flow of current through cut-out 13 lifts the armature 14 and demagnetizes solenoid 6, thereby allowing plunger 8 to rise by its own buoyancy. This movement causes the upper edge of cup 11 to cut through the mercury layer, and thus separate the mercury on the outside of the cup from that on the inside. This movement does not, however, destroy the electrical connection between these two bodies of mercury for an arc is established at this point and current continues to flow 80 from one mercury surface to the other. This starting arc renders conductive the space within the tube so that the flow of current takes place from anode 2 to cathode 3, and the lamp then operates in the usual manner. 90

The solenoid 6, it will be observed, is connected in shunt to the mains only momentarily while the lamp is being started. It may therefore be made of relatively very small wire as it is not under the influence of current long enough to become unduly heated.

The protecting sleeve 12 of glass around the lower end of filament 4, while it may be omitted, has the advantage that it with certainty confines the starting arc entirely to the mercury surfaces, so that no action destructive to the filament can occur no matter how long this arc may continue to exist before the lamp starts.

In lamps as heretofore constructed some 116

difficulty has been experienced in the carelessness of workmen in connecting the lamps in circuit with the terminals reversed. If such a mistake is made in connecting up a 5 lamp of the type in which a moving filament establishes an incipient arc at the surface of the mercury electrode, there is danger that this arc will continue to play on the filament as cathode without starting the 10 lamp, and will consequently burn off the lower end of the filament. This difficulty is entirely overcome by my improved construction in which the incipient arc always occurs between mercury surfaces no matter 15 whether the lamp is properly connected up or not.

What I claim as new and desire to secure by Letters Patent of the United States, is,—

1. In a vapor electric apparatus, an evacuated chamber, a mercury electrode therein, a stationary high resistance filament in said chamber, a conducting body electrically connected to said filament but insulated from said electrode, and means for automatically 20 establishing electrical connection between said conducting body and said electrode.
2. In a vapor electric apparatus, an evacuated chamber, a mercury electrode therein, a filament in said chamber, a body of mercury electrically connected to said filament but separated from said electrode by an insulator, and automatic means for moving said body of mercury into electrical connection with said mercury electrode. 25
3. In a vapor electric apparatus, a mercury electrode, a plunger floating in said mercury electrode, a body of conducting liquid carried by said plunger and insulated from said mercury electrode, a filament dipping in said conducting liquid, and means for moving said plunger. 30
4. The combination of an evacuated envelop, electrodes therein, means within said envelop for establishing a direct connection 45 between said electrodes through a solid conductor, and means for severing said connection between surfaces of vaporizable material.
5. In a vapor electric apparatus, a mercury electrode, a plunger of insulating material floating in said mercury electrode, a body of conducting material carried by said plunger, and automatic means for producing a momentary contact between said mercury 50 electrode and said body of conducting material.
6. In a vapor electric apparatus having a mercury electrode, a second body of mercury movable with respect to said mercury electrode, a high resistance filament dipping in said second body of mercury, and automatic means for producing a momentary contact between said mercury electrode and said second body of mercury. 60
7. In a vapor electric apparatus, a mer- 65

cury electrode, a plunger suspended in said mercury electrode, a body of conducting material carried by said plunger and insulated from said mercury electrode, and automatic means for moving said plunger to produce a momentary contact of said body of conducting material with said mercury electrode. 70

8. In a vapor electric apparatus, a mercury electrode, a plunger suspended in said mercury electrode, a body of conducting material carried by said plunger and insulated from said mercury electrode, a high resistance filament electrically connected to said body of conducting material, and means for moving said plunger to establish an electrical connection between said filament and said mercury electrode. 75

9. In a vapor electric apparatus, an evacuated chamber, an anode and a mercury cathode therein, a source of current connected to said cathode, a second body of mercury connected to the other side of said current source, and means for lowering said second body of mercury into contact with said mercury electrode and subsequently raising the same to produce an incipient or starting arc 80 in said evacuated chamber.

10. In a vapor electric apparatus, an evacuated chamber, a mercury electrode therein, a high resistance filament in said chamber, a non-conducting tube inclosing one end of said filament, means for electrically connecting said end of the filament with the mercury electrode, and means for breaking contact between a portion of the body of mercury engaging said filament and the main body of mercury. 85

11. In a vapor electric apparatus, an evacuated chamber, a mercury electrode therein, a plunger suspended in said mercury electrode and carrying a second body of mercury, a filament dipping in the mercury carried by said plunger, and means for moving said plunger to produce an arc between said electrode and the mercury carried by said plunger. 90

12. In a vapor electric apparatus, an evacuated chamber, a high resistance filament therein, a plurality of mercury bodies therein, means for producing an arc between said mercury bodies by current carried by said filament, and means for protecting said filament from the destructive action of said arc. 95

13. In a vapor electric apparatus, an evacuated receptacle, a mercury electrode therein, a conductor extending below the surface of the mercury, and means interposing a movable barrier of insulating material between said conductor and a portion of said body of mercury. 100

14. In a vapor electric apparatus, an evacuated receptacle, a mercury electrode therein, a conductor extending below the surface of the mercury, and magnetically 105

controlled means for interposing a barrier of insulating material between said conductor and a portion of said body of mercury.

- 5 15. The combination of an evacuated envelop, electrodes therein, at least one of which is of vaporizable material, a solid conductor initially carrying current within said envelop, means for connecting said solid conductor with said vaporizable electrode and for severing said connection between surfaces of vaporizable material.
16. The combination of an evacuated envelop, electrodes therein at least one of which is of vaporizable material, a solid conductor within said envelop, means for establishing a path for current between said electrodes by way of said solid conductor, and means for producing an arc between said electrodes by initiating a starting arc in said path between surfaces of similarly vaporizable material.
17. The combination of an evacuated envelop, electrodes therein at least one of which is of vaporizable material, means for passing current directly from one electrode to the other through a solid conductor located within the envelop, and means for forming an arc in said envelop in series with said solid conductor between surfaces of vaporizable material.
18. In a vapor electric apparatus, an evacuated receptacle, a vaporizable electrode therein, means for passing current through said electrode and means for then moving an insulating barrier to separate
- portions of said electrode and establish an arc therebetween.
19. In a vapor electric apparatus, an evacuated receptacle, a vaporizable electrode therein, a cup of insulating material movable to withdraw a portion of said vaporizable material, and means for moving said cup.
20. In a vapor electric apparatus, an evacuated envelop, a mercury electrode and a solid electrode therein, a mercury body permanently connected to said solid electrode by a conductor located within said envelop, and means for producing a relative movement between said mercury electrode and said mercury body to initiate an arc to said solid electrode.
21. In a vapor electric apparatus, an evacuated envelop, a body of vaporizable material therein initially out of contact with said envelop, means for lowering said body, and means for starting an arc in said envelop when said body rises.
22. In a vapor electric apparatus, an evacuated envelop, a fluid body therein, a plunger floating in said fluid, means for depressing said plunger, automatic means for releasing said plunger, and means for starting an arc when said plunger is released.
- In witness whereof, I have hereunto set my hand this 28th day of March, 1905.

LEONARD E. DEMPSTER.
